Primary Examiner—Bernard Ansher*Assistant Examiner*—Philip Hyder*Attorney, Agent, or Firm*—Marshall, O'Toole, Gerstein, Murray & Bicknell[57] **CLAIM**

The ornamental design for a tool handle, as shown and described.

DESCRIPTION

FIG. 1 is a perspective view of a tool handle showing my new design;

FIG. 2 is a top plan view thereof;

FIG. 3 is a side elevational view thereof;

FIG. 4 is a front elevational view thereof; and,

FIG. 5 is a bottom plan view thereof.

The broken line showing of the handle is for illustrative purposes only and forms no part of the claimed design.
